ROTARY ENGINE

John Edwin Raymond, Hamilton, Ontario, Canada

Application February 4, 1937, Serial No. 124,061

10 Claims. (Cl. 123—8)

My invention relates to improvements in rotary engines of the type in which a spherical shell is divided into compartments by a pair of intersecting plates in such manner that the volumes of the compartments change on revolution of one plate about a diameter while the other plate rotates about its axis.

An object of my invention is to provide in such an engine a seal and bearing at the intersection 10 of the plates which will permit the plates to revolve about their respective axes and at the same time maintain an efficient seal between the four compartments.

Another object is to provide in such an engine means whereby the ratios between the maximum and minimum volumes of each compartment may be varied at will, either while the engine is idle or in operation.

Another object is to devise such an engine 20 which may be driven by the explosion of fuel vapour in a chamber located externally of the spherical shell communication of which with the shell compartments is controlled by valves whereby a highly effective power cycle is provided in 25 the engine.

A further object of my invention is to provide a device of the character herein described which may be used as a rotary engine or by slight modification of the valves as a pump.

With the above and other objects in view which will hereafter appear as the specification proceeds, my invention consists, in a preferred embodiment, of the construction and arrangement all as hereafter more particularly described and 35 illustrated in the accompanying drawings, in which:

Fig. 1 is a side elevational view of my improved engine broken away to show parts thereof in section;

Fig. 2 is a horizontal sectional view taken along the line 2—2 of Fig. 1, certain parts being shown in elevation;

Fig. 3 is a vertical sectional view taken along the line 3—3 of Fig. 2;

Fig. 4 is a vertical sectional view of my engine taken along the line 4—4 of Fig. 5, showing my improved means for varying the compression ratio, and with some of the details of the previous figures omitted for the sake of clarity of 50 illustration; and

Fig. 5 is a vertical sectional view therethrough taken along the line 5—5 of Fig. 4.

Like characters of reference designate corresponding parts in the different views.

Referring to the drawings, and particularly to

Figs. 1, 2 and 3, a pair of hemispherical shells 1 and 2 form a hollow sphere which is divided into expansion chambers by a revoluble disc 3 which passes through a slot 17 in a disc 4 which is fixed as to position but which is rotatable about the normal through its centre. The disc 3 is provided with trunnions 5 and 6 which are received in bearings 7 and 8 in the respective shells 1 and 2, and a bearing for the disc 4 is formed by flanges 9, 9 on the shells 1 and 2 between which the margin of the disc 4 is received, the flanges being spaced apart by an annular ring 10 to prevent binding of the disc as it rotates.

The discs 3 and 4 are required to make a 15 pressure-tight seal with the wall of the sphere formed by the shells 1 and 2, and with each other, and to this end the margin of the disc 3 may be provided with conventional sealing means such as rings 11, and the intersection of 20 the discs 3 and 4 may be sealed by a cylindrical member 12 provided with journals 13 which are received in sockets 14 in the disc 4, and also with a longitudinal slot 15 through which the disc 3 passes being held rotatably positioned therein 25 by means of a pivot pin 16, which is a press fit in the hole 16a in the centre of the disc 3 and which extends on each side of it into the bearing sockets 12a and 12b (Fig. 3) of the cylindrical member. The cylindrical member 12 forms 30 a seal between the discs 3 and 4 by close contact with the arcuate surfaces of the slot 17 in the disc 4.

It will be observed that the intersecting discs 3 and 4 divide the sphere formed by the shells 1 and 2 into four chambers which will vary in 35 volume as the plate 3 is revolved, and in the preferred form of my engine I provide bosses 18 on each side of the disc 4 which substantially fill the diametrically opposite chambers when the disc 3 is in such position that such chambers are of minimum volume, i. e., when the disc 3 is in the position illustrated in Figs. 1 to 3 inclusive.

In the wall of the sphere formed by the shells 1 and 2 are provided four ports 19, 20, 21 and 45 22, each disposed substantially on a diametrical plane of the sphere and adjacent to the axis of revolution of the disc 3. The port 19 is connected to a source of supply of explosive vapour, such as a carburetor (not shown) and the port 20 is adapted to exhaust gases from the sphere. The ports 21 and 22 are connected by an explosion chamber 23 in which means such as a spark-plug 24 may be provided for exploding vapour in the chamber, and the port 21 is also provided 50 55

with a valve 25 normally held closed by a spring 26, and adapted to be opened by gas pressure in the sphere. The port 22 is adapted to be closed by a rotary valve 27 carried by the disc 3 and disposed in a recess 28 in the shell 2 surrounding the trunnion 6, an arcuate slot 29 in the valve 27 serving to open the port 22 when it is in register therewith.

The operation of my engine in the form illustrated in Figs. 1 to 3 inclusive is as follows:

The engine is cranked to start it in the same manner as a conventional reciprocating internal combustion engine. As the disc 3 revolves clockwise Figs. 1 and 2 about its diameter, chamber A 15 bounded by the discs 3 and 4 and the wall of the sphere formed by the shells 1 and 2 comes into communication with the port 19 when the volume of the chamber is a minimum. Continued revolution of the disc 3 causes the volume of the 20 chamber to increase, thereby drawing a charge of explosive vapour from the carburetor into the chamber. As the volume of the chamber reaches a maximum, the margin of the disc 3 crosses the port 19 and cuts it off from communication 25 therewith and simultaneously the margin of the disc crosses the port 21 to place the chamber in communication therewith. The spring 26 holds the valve 25 in the port 21 closed until continued revolution of the disc 3 has caused the 30 volume of the chamber to decrease to such an extent that the pressure of the vapour charge therein has become greater than that of the expanding burned gases from the previous explosion in the chamber 23 and in the expansion chamber B which is now in communication with the open port 22. The valve 25 is therefore forced to open and the new charge is expelled from the decreasing compression chamber A through the port 21 into the chamber 23 driving 35 the burned gases ahead of it out through the port 22 into the increasing volume of the expansion chamber B. The rotary valve 27 is arranged to close the port 22 before any of the new charge passes through it and the burned gases are now further expanded during the 40 remainder of the expansion stroke in the now isolated expansion chamber B. Simultaneously the remainder of the new charge is completely expelled from the compression chamber A through 45 the still open port 21 into the chamber 23 thereby increasing the pressure of the explosive vapour therein to the desired pre-ignition value. At this time the margin of the disc 3 crosses the port 21 and brings into communication therewith, at its point of maximum volume, the chamber A₁ the low pressure within which allows the relatively high pressure in the chamber 23 to operate the valve 25 and close the port 21. At the same instant the expansion chamber 50 B containing the fully expanded burnt gases is brought into communication with the port 20, through which they are expelled, and simultaneously a chamber B₁ of minimum volume is brought into communication with the chamber 23 which contains the compressed fuel charge. With the port 22 open, this charge is exploded by the spark-plug 24, and the pressure in the chamber 23 and the communicating expansion chamber B₁ isolated by the discs 3 and 55 4 rises sharply and provides a power impulse tending to cause the volume of the latter chamber to increase and cause the disc 3 to revolve. This cycle of operations is repeated continuously once initiated by cranking of the engine, and

power developed by the revolution of the disc 3 is transmitted through the trunnion 6.

It should be obvious from the foregoing description that of the four chambers into which the sphere formed by the shells 1 and 2 is divided by the intersecting discs 3 and 4, the pair on the left of Fig. 1 are used only to draw fuel vapour from the carburetor or other source and compress it into the chamber 23; and the pair to the right of Fig. 1 are used as expansion chambers in which the energy of the explosions taking place in the chamber 23 is utilized. As illustrated then, the engine is analogous to a two cylinder two-stroke-cycle reciprocating engine.

In Figs. 4 and 5 is illustrated a means whereby the compression ratios of the chambers of any engine of this type may be varied from unity to a substantially infinitely high value.

Referring to such figures, the device comprises the hollow sphere formed by shells 30 and 31 provided with the intersecting discs 3 and 4 as previously described. In this exemplification, however, while the trunnions 5 and 6 are carried by the shells 30 and 31, the disc 4 is rotatable about its axis in a groove 32 in a spherical shell 33 which closely engages the inner walls of the shells 30 and 31. The shell 33, which may be composed of more than one piece to facilitate assembly of the engine, is provided with an equatorially disposed flange 34 which is received in a groove 35 in the inner periphery of the sphere formed by the shells 30 and 31, such groove being coplanar with the axis of the trunnions 5 and 6. Teeth 36 in the flange 34 are engageable with a worm 37 carried by an actuating shaft 38 journalled in a pressure tight housing 39 on one of the shells 30 or 31, and terminating in a hand-wheel 40. Slots 41 are provided in the shell 33 through which the trunnions 5 and 6 pass and which permit the shell 33 to revolve a limited extent within the shells 30 and 31, when the hand-wheel 40 is rotated. Bosses 42 may be provided on the disc 3 which overlie and seal the slots 41 and also serve the same purpose as the bosses 18 in the first described embodiment of the engine.

It will be obvious that the features of Figs. 4 and 5 may be incorporated in an engine such as is disclosed in the other figures. In such case, then, by rotating the hand-wheel 40, the shell 33 may be revolved within the outer sphere, thereby varying the maximum and minimum angles between the discs 3 and 4 as the disc 3 revolves and thus changing the ratio between the minimum and maximum volumes of each of the four compartments formed by the intersecting discs on revolution of the disc 3. The power output of the engine may be controlled very smoothly by this means, between zero and the maximum possible, as when the shell 33 is in such position that the disc 3 remains at approximately right angles to the axis of revolution of the disc 4 while the disc 3 revolves there is only a very slight change in the volume of each of the chambers formed by the discs during each revolution of the disc 3, and very little work is done by the expanding gases during the cycle; as the angle between the disc 3 and the axis of the disc 4 is decreased, the volume charge of each of the chambers increases, thereby increasing the work done by the expanding gases.

An advantage of an engine constructed according to my invention is that its power output may be varied from zero to maximum as rapidly or as slowly as may be desired, so that no vari-

able ratio gear unit or equivalent device is required in order to adapt the engine to changing load conditions.

Yet another advantage of the device is that the combustion of the fuel therefor takes place in a relatively isolated chamber, so that the moving parts of the engine are not exposed to as high temperatures as when they are in contact with the burning gases.

10 While I have described my invention with reference to a particular embodiment, I realize there are many other ways in which the novel features disclosed therein may be employed, and I therefore wish my disclosure to impose no limitations 15 on the scope of the invention beyond those set forth in the appended claims.

What I claim as my invention is:

1. In a rotary engine comprising a hollow spherical shell divided into compartments by 20 a pair of intersecting plates, one of which is revoluble about a diameter thereof and the other of which is rotatable about a central axis normal to the plane of the plate, adjustable means for varying the angle made by the latter plate 25 with the axis of revolution of the first plate.

2. A rotary engine comprising a hollow spherical shell divided into compartments by a pair of intersecting plates, one of which is revoluble about a diameter thereof and the other of which 30 is rotatable about a central axis normal to the plane of the plate, means for rotatably positioning the second plate therein, an outer substantially spherical shell closely overlying the first shell, means for rotatably positioning the first 35 plate therein, and adjustable means for rotating the inner shell within the outer shell whereby the angle made by the second plate with the axis of revolution of the first plate may be varied.

40 3. A rotary engine as claimed in claim 2 wherein in the means for rotating the inner shell comprises an equatorially disposed flange thereon, a similarly disposed groove in the outer shell in which the flange is received, such groove being 45 coplanar with the axis of revolution of the first plate, teeth on the flange, a worm gear journaled in the outer shell and engageable with the teeth on the flange, and means disposed externally of the outer shell for rotating the worm 50 gear.

4. A rotary engine comprising a hollow shell divided by a pair of intersecting plates; one of which is revoluble about a diameter and the other of which is rotatable about its axis which is disposed at an angle to such diameter; into four compartments the volume of each of which varies on revolution of the first plate, means for admitting an explosive vapour fuel charge into the shell for compression in either one of one pair 55 of adjacent compartments, an explosion chamber disposed exteriorly of the shell, means for admitting each fuel charge during compression into the explosion chamber at such a time that it will force the exploded fuel charge therein 60 into the one of the other pair of adjacent compartments which is increasing in volume, means for interrupting the transfer of exploded fuel charge into the expanding compartment before any of the explosive vapour has entered the expanding compartment, means for interrupting the connection between the compression compartments and the combustion chamber after each fuel charge has been admitted, means for connecting the explosion chamber to each expansion chamber when its volume has reached a 70

minimum, means for exploding the fuel charge within the explosion chamber, and means for exhausting the products of combustion from each expansion compartment after its volume has become a maximum.

5 5. In a rotary engine comprising a hollow shell divided into compartments by a pair of intersecting plates, one of which is revoluble about a diameter and the other of which is rotatable about its axis and is provided with a slot for the reception of the revoluble plate, combined sealing and bearing means for the intersection of the plates comprising a cylindrical sealing member journaled in the rotatable plate and having a slot therethrough in which the revoluble plate is received in fluid tight relation, means for forming a fluid tight seal between the surface of the cylindrical member and the slot in the rotatable plate, and a pivot pin disposed transversely of and rotatably secured within the cylindrical member extending through and being immovably fixed within a central hole in the revoluble plate.

10 6. In a rotary engine as claimed in claim 1, combined sealing and bearing means for the intersection of the plates comprising a cylindrical sealing member journaled in a slot in the rotatable plate and having an opening therethrough in which the revoluble plate is received in fluid tight relation, means for forming a fluid tight seal between the surface of the cylindrical member and the slot in the rotatable plate, and a pivot pin disposed transversely of and rotatably secured within the cylindrical member extending through and being immovably fixed within a 15 central hole in the revoluble plate.

20 7. In a rotary engine as claimed in claim 4, combined sealing and bearing means for the intersection of the plates comprising a cylindrical sealing member journaled in a slot in the rotatable plate and having an opening therethrough in which the revoluble plate is received in fluid tight relation, means for forming a fluid tight seal between the surface of the cylindrical member and the slot in the rotatable plate, and a pivot pin disposed transversely of and rotatably secured within the cylindrical member extending through and being immovably fixed within a 25 central hole in the revoluble plate.

30 8. A machine of the kind described, comprising a casing having a spherical opening therein, a revoluble disc within the opening provided with two diametrically opposite trunnions affixed thereto and extending into bearings in the casing, a second disc crossing said opening at 35 an oblique angle with respect to the axis of revolution of the first disc and intersecting it on a diameter thereof, a groove around the inside of the spherical opening in the plane of the second disc, the rim of the said second disc extending 40 into the groove and permitting rotation only about an axis normal to its plane, a cylindrical sealing member journaled into the second disc with its axis along the line of intersection of the two discs, a longitudinal slot in the cylindrical member through which the first disc passes in fluid tight relationship, and a pivot pin journaled transversely in the cylindrical member about which the first disc revolves.

45 9. A machine of the kind described comprising a casing having a spherical opening therein, a revoluble disc within the opening provided with two diametrically opposite trunnions affixed thereto and extending into bearings in the casing, a second disc crossing said opening at 50

an oblique angle with respect to the axis of revolution of the first disc and intersecting it on a diameter thereof, a groove around the inside of the spherical opening in the plane of the second disc, the rim of the said second disc extending into the groove and permitting rotation only about an axis normal to its plane, a cylindrical sealing member journalled into the second disc with its axis along the line of intersection of the two discs, a longitudinal slot in the cylindrical member through which the first disc passes in fluid tight relationship, a pivot pin journalled transversely in the cylindrical member about which the first disc revolves, and inlet and outlet ports through the casing to the spherical opening.

10. A rotary engine of the kind described comprising a casing having a spherical opening therein, a revoluble disc within the opening provided with two diametrically opposite trunnions affixed thereto and extending into bearings in the casing, a second disc crossing said opening at an oblique angle with respect to the axis

of revolution of the first disc and intersecting it on a diameter thereof, a groove around the inside of the spherical opening in the plane of the second disc, the rim of said second disc extending into the groove and permitting rotation only 5 about an axis normal to its plane, a cylindrical sealing member journalled into the second disc with its axis along the line of intersection of the two discs, a longitudinal slot in the cylindrical member through which the first disc passes in fluid tight relationship, a pivot pin journalled transversely into the cylindrical member about 10 which the first disc revolves, inlet and outlet ports through the casing to the spherical opening, and a combustion chamber disposed between an outlet and an inlet port in such a manner that two compartments act as compressors feeding the combustion chamber and the other two compartments act as expansion compartments for the combustion chamber after combustion 15 has taken place.

JOHN EDWIN RAYMOND.
